2 Sheets-Sheet 2

Patented May 15, 1923.

1,455,500

UNITED STATES PATENT OFFICE.

JOSEPH LEWIS, OF WINNIPEG, MANITOBA, CANADA.

REGISTER FOR PRINTING MACHINES.

Application filed May 3, 1919. Serial No. 294,447.

To all whom it may concern:

Be it known that I, JOSEPH LEWIS, of the city of Winnipeg, in the Province of Manitoba, Canada, have invented certain new and useful Improvements in Registers for Printing Machines, of which the following is the specification.

The invention relates to improvements in attachments to printing machines, and particularly to counting attachments, and the principal object of the invention is to provide a counting attachment associated with the delivery end of a folding press which will actually count the sheets passed to the folding end of the press, with the result that one, in using this appliance, has an accurate record of all the sheets actually delivered and exclusive of those destroyed in or removed from the machine as often occurs.

20 A further object of the invention is to construct a counting attachment particularly adaptable to folding presses, such as a Hoe press, the counter being arranged such that it is released or unlocked by the delivered sheet and allowed, when unlocked, to count, the movement taking place when the folding blade goes down.

25

With the above objects in view, the invention consists essentially in the arrangement and construction of parts hereinafter more particularly described and later pointed out in the appended claim, reference being had to the accompanying drawings in which:—

Fig. 1 represents a plan view of the delivery end or folding table of a folding press with my invention applied thereon.

Fig. 2 represents a sectional view through the folding table, the section being taken at X—X' Fig. 1.

Fig. 3 represents an enlarged detailed side view of the counter and a portion of the folding blade and showing the counter in the locked position, and the blade up.

Fig. 4 represents a plan view of the parts appearing in Fig. 3.

Fig. 5 represents an end view of the counter.

Fig. 6 represents a reverse view of the end of the folding blade to that shown in Fig. 3.

50 In the drawings like characters of reference indicate corresponding parts in the several figures.

I might here state that I have already filed an application for a counting attachment particularly constructed for use on a flat bed press such as the Miehle press, the ap-

plication being filed in the United States Patent Office under No. 249,293, the 10th of August, 1918.

The present invention which embodies a counter very similar to that disclosed in the former application has special adaptations, making it particularly applicable to a folding press such as the Hoe press already mentioned. As a press of this kind is well known I have not considered it necessary to minutely enter into the details thereof but have only herein shown and described the delivery end in so far as the parts associated with my invention are concerned.

70 Referring now to the drawings:—

1 represents the folding table of a press which is supplied at the sides with delivery tapes 2 and 3 operated by the press mechanism and designed to deliver the sheets on to the table, the sheets being stopped by the sheet stop 4 located towards the end of the table. The table is provided with a lengthwise extending slot 5 positioned directly beneath the folding knife 6 which is suspended by swinging cranks 7 and 8 from elevated cross shafts 9 and 10 mounted in the sides of the table.

75 11 represents an operating crank extending from the shaft 9 and connected by a rod 12 to an operating part of the press which forms no part of my invention but which is designed to swing the crank 11 at a proper time inwardly and outwardly to effect the up and down movement of the blade this 80 occurring after the sheet has been delivered by the tapes on to the table.

85 From this arrangement it is obvious that each sheet delivered will be folded and pressed down through the slot 5 by the blade 6. The up and down movement of the blade and a delivered sheet are the only parts of the folding press on which I rely to actuate my counter.

90 The counting appliance indicated generally by the reference numeral 13 is permanently fastened by screws 14 to the table in a location adjacent the end of the folding blade and it comprises the following parts:—

100 15 represents a counter of any approved type which is provided with sight openings 16 through which the numbers on the several discs 17 of the counter can be clearly seen. The counter and the details of it form 105 no part of my invention.

110 Such a counter is usually supplied with a

resetting thumb piece 18, a counting shaft 19 and an actuating countershaft 19', the countershaft being fitted with pinions engageable with gears associated with the discs 5 and the arrangement being such that each time the countershaft is turned a portion of a revolution a disc moves and the counter counts.

To the end of the shaft 19' I secure a T-shaped controlling lever 20 which has a long and a short end, the short end being fitted with a notch 21 and the long end extending towards the upper part of the blade 6 and normally engaging an angle plate 22 fastened by the bolt 23 to the end of the blade, the arrangement being such that when the blade is in its uppermost position and the lever is resting on the plate 22 the counter is in an inert position and set so that the 20 numbers can be clearly seen through the sight openings.

A coiled spring 25 extends between the long arm of the lever and the base 26 of the counter, this spring serving to pull down on 25 the long end of the lever and cause it, unless otherwise locked to follow down with the blade 6. The full down movement of the blade is designed to effect sufficient swing in the lever to cause the shaft 19' to turn an 30 amount sufficient to actuate the counter discs and register.

27 represents a substantially L-shaped trip lever pivotally mounted on a pin 28 carried by the base 26 and 29 represents an outstanding rod attached to the lever and provided with an adjustable weight 30. The upper end of the lever 27 is provided with a shoulder 31 engageable in the non-counting position of the long arm of the lever 20 with 35 a catch 32 in the nature of an angle bracket permanently secured to the lever 20. The lower end of the lever 27 extends towards the blade and is formed with a tripping foot 33 positioned somewhat in advance of the sheet 40 stop 4 so that the oncoming sheet passing between the blade and the table will strike the foot piece and carry it with it prior to reaching the sheet stop. The movement so produced by the oncoming sheet is utilized to 45 release the lever 20 by withdrawing the shoulder 31 from beneath the angle bracket 32.

Here it will be noticed that the outer edge of the lever 27 next the shoulder presents an 55 inclined face 34. The angle bracket is designed to travel down this face once released from the shoulder and push the engaged upper end of the lever inwardly on the down travel of the angle bracket. During this 60 movement the weight 30 is acting to hold the upper end of the lever against the bracket.

35 represents a locking bar pivotally secured at 36 to the base 26 of the counter and provided with a pin 37 designed in the upper 65 swung position of the bar to enter the notch

21 and positively lock the long end of the lever 20 against downward swinging.

The operation of the counting attachment is now described, assuming the press in operation and a sheet being delivered on to the 70 table by the tapes and that the sheet is actually stopped by the sheet stop 4 before the blade starts its downward travel.

As the oncoming sheet passes towards its final position against the sheet stop the oncoming edge strikes the foot 33 and swings the lever 27 in a direction such that the shoulder 31 is passed from beneath the bracket 32. Accordingly when the blade 75 starts its downward travel the long end of the lever swings down with it under the action of the spring 25 and effects the operation of the counter through the movement of the shaft 19'.

In the up travel of the blade the lever 20 80 is returned to its original position and the shoulder 31 of the lever 27 passes back beneath the bracket 32, as during the up and down movement the angle bracket 32 travels the inclined edge 34 of the lever and accordingly 85 is ready to enter the notch as soon as the notch presents itself, the weight 30 controlling this action.

Accordingly then, each time the sheet is delivered the locking lever 27 and the 90 shoulder 21 are placed in locking position. Should no sheet however be delivered the trip lever 27 will not be actuated and accordingly as the long end of the lever 20 moves down with the knife it is caught by 95 the shoulder 31 and is locked in its up non-counting position and this even although the blade 6 may make an idle stroke.

If one wishes to operate the press without 100 counting the delivered sheets he simply swings the arm 35 up to engage the pin 37 in the notch 21 and thereby locks the lever 20 against movement irrespective of whether the foot 33 is tripped or not.

What I claim as my invention:

In a folding press, the combination with a 110 paper delivering means, a counter, and a moving, paper folding member, of a controlling lever connected to the counter and normally engaging the folding member and adapted to follow the movement thereof to effect the operation of the counter and a self-setting trip lever normally engaging and locking the controlling lever against movement and provided with a foot piece extending into the path of the delivered paper and adapted to be actuated thereby to release the controlling lever and permit it to follow the movement of the folding member.

Signed at Winnipeg, this 23 day of April, 120 1919.

JOSEPH LEWIS.

In presence of:—

G. S. ROXBURGH,
E. H. SIGVALDASON.
